US00D955598S

(12) **United States Design Patent** (10) **Patent No.:** **US D955,598 S**
(45) **Date of Patent:** **** Jun. 21, 2022**

(54) **MEDICAL TESTING DEVICE**

(71) Applicant: **Lucira Health, Inc.**, Emeryville, CA (US)

(72) Inventors: **Clay David Reber**, Berkeley, CA (US); **Christopher Frank Kelly**, Larkspur, CA (US); **Frank Benson Myers, III**, Richmond, CA (US); **Ragheb El Khaja**, Oakland, CA (US); **John Robert Waldeisen**, Berkeley, CA (US); **Debkishore Mitra**, Emeryville, CA (US)

(73) Assignee: **Lucira Health, Inc.**, Emeryville, CA (US)

(**) Term: **15 Years**

(21) Appl. No.: **29/759,253**

(22) Filed: **Nov. 20, 2020**

Related U.S. Application Data

(63) Continuation of application No. 29/674,581, filed on Dec. 21, 2018, now Pat. No. Des. 907,232.

(57) **CLAIM**

The ornamental design for a medical testing device, as shown and described.

DESCRIPTION

FIG. 1 is top, left, front perspective view of a medical testing device;

FIG. 2 is a bottom, left, front perspective view thereof;

FIG. 3 is a top, right, rear perspective view thereof;

FIG. 4 is a top plan view thereof;

FIG. 5 is a bottom plan view thereof;

FIG. 6 is a left side elevational view thereof;

FIG. 7 is a right side elevational view thereof;

FIG. 8 is a rear elevational view thereof; and,

FIG. 9 is a front elevational view thereof.

The broken lines depict portions of the medical testing device that form no part of the claimed design.

1 Claim, 9 Drawing Sheets
